[57] CLAIM

The ornamental design for a keyhole escutcheon, as shown.

DESCRIPTION

FIG. 1 is a front elevational view of a keyhole escutcheon incorporating my new design;

FIG. 2 is a side elevational view taken from the right of FIG. 1, the side opposite being a mirror image thereof; FIG. 3 is a bottom plan view, the top view being identical;

FIG. 4 is an enlarged sectional view taken along the line 4—4 in FIG. 1.

FIG. 5 is an enlarged sectional view taken along the line 5—5 in FIG. 1.

FIG. 6 is an enlarged sectional view taken along the line 6—6 in FIG. 1.

FIG. 1.

FIG. 2.

FIG. 3.

FIG. 4.

FIG. 5.

FIG. 6.
